UNITED STATES PATENT OFFICE.

CHARLES H. STRUEBIG, OF MILWAUKEE, WISCONSIN.

MAT FOR SEED-PRESSES.

SPECIFICATION forming part of Letters Patent No. 321,258, dated June 30, 1885.

Application filed May 4, 1885. (No model.)

To all whom it may concern:

Be it known that I, CHARLES H. STRUEBIG, of Milwaukee, in the county of Milwaukee, and in the State of Wisconsin, have invented 5 certain new and useful Improvements in Mats for Seed-Presses; and I do hereby declare that the following is a full, clear, and exact description thereof.

My invention relates to mats for oil-presses, 10 and will be fully described hereinafter.

In the drawings, Figure 1 is a plan view of the frame upon which my improved mats are made, showing a partly-completed mat thereon. Fig. 2 is a plan view of the completed mat. Fig. 3 is a plan view of a needle, and Fig. 4 is a plan view of the compressing mechanism with a partly-finished mat therein.

A A' A² A³, &c., are needles, which in the first stage of the construction of a mat are 20 clamped between plates B B' at their center, the latter plate carrying lugs b, each pair of which separates each needle from its neighbor, the plates B B' being held together by screw-clamps C. After these needles have 25 been placed in the clamps the operators may work on the frame at once, each beginning at the plates B B' and working outward, as follows: The rope used is of hair, and the end of each rope is spliced about an outer needle, 30 and then, starting at A, the rope a is passed under needles A' A², over needles A³ and A⁴, under needles A⁵ A⁶, over A⁷ and A⁸, under A⁹ A¹⁰, over A¹¹ A¹², under A¹³ A¹⁴, and over A¹⁵, back under A¹⁴, over A¹³ and A¹², under 35 A¹¹ and A¹⁰, and so on until the border is reached, and then the rope a, starting at A¹⁵, is 40 passed over A¹⁵, under A¹⁴, over A¹³, under A¹², and so on, passing under A and back over and under alternate needles until it reaches A¹⁵ again, where it is spliced. In this last row 45 the rope is twisted upon itself with a needle between each twist.

The lower half of Fig. 1 gives the appearance of the mat at this last-described stage 45 with the lines of rope parted from each other, while the upper portion gives the appearance of the same after the lines have been pressed together by hand, or, in other words, "worked close."

The next stage in the manufacture consists 50 in removing plate B and lifting the half-fin-

ished mat from it and then placing it on frame D. The frame D is rectangular, and has lugs d at or near each corner to receive screw-shafts E, and a bar, F, extends across one end 55 of the frame, and is provided with pins or lugs f, similar to those on plate B', while another bar, F', having screw-threaded openings through its ends, is arranged parallel with bar F, and a shaft, E, is passed through each 60 of these openings. Except that bar F' travels on screw-shaft E, it is just like bar F, having a row of lugs or pins arranged along its entire length, and when the mat is laid on the frame the ends of the needles lie with each 65 pair separated by a lug or pin. Now, by means of a crank on each shaft E, the two shafts are turned and the bar F' screwed up toward the bar F, and the two sections of the 70 mat are compressed into one compact mass. 75 Then, by means of the needles A A' A², &c., each of which has an eye at each end to receive the tapered end of a rope, G, the body of which is of about the diameter of the needles, the rope G, beginning in the middle, is 75 carried through the fabric to take the place of the needles, and after being drawn tightly is interlaced at the terminal corners of the 80 mat, and the result is a complete mat, H. It will be noted that the surface of the mat is 85 raised, as at h, on each edge of the mat. This is to give additional strength to the structure, and is produced by increasing the diameter of the rope of each section, as shown in the lower half of Fig. 1.

When the mat is in the press, the raised portions h lie outside of the edges of the compressing-plate.

Mats made according to my invention present a practically even and level surface to 90 the press, and are very strong and durable. The ropes or cords in the sections of the mat are twisted in opposite directions to keep the mat from warping in process of construction.

Having thus fully described my invention, 95 what I claim as new, and desire to secure by Letters Patent, is—

1. A mat for presses, &c., consisting of a series of longitudinal cords interlaced about a series of transverse cords, then compressed and bound together by the transverse cords, as set forth.

2. In a mat, the combination of the transverse cords with the longitudinal cords, the latter interlaced with the former, and having increased diameters toward their outer ends.
- 5 3. A mat formed with side ridges and intermediate level surface, as described.
- In testimony that I claim the foregoing I

have hereunto set my hand, at Milwaukee, in the county of Milwaukee and State of Wisconsin, in the presence of two witnesses.

CHARLES H. STRUEBIG.
